ATTORNEY

UNITED STATES PATENT OFFICE.

GEORGE G. GOING, OF MIDDLETOWN, CONNECTICUT, ASSIGNOR TO REMINGTON NOISELESS TYPEWRITER CORPORATION, OF NEW YORK, N. Y., A CORPORATION OF NEW YORK.

TYPEWRITING MACHINE.

Application filed August 28, 1925. Serial No. 53,101.

My invention relates to typewriting or like machines, and more particularly to card clamps by which a card or like comparatively stiff or heavy work sheet may be held snug against the face of the platen as it is being fed with the platen, as the latter is rotated.

The main object of the invention is to provide a simple yet highly efficient card clamp and attaching means therefor, of such a character that the card clamp may be readily attached to the platen for use in feeding cards and when detached from the platen leaves the latter in condition for ordinary use.

A further and important object of my invention is to provide a card clamp and fastening means therefor of the character specified which enables the card clamps to be readily applied to existing platens without reconstructing, altering, or mutilating such platens, or other features of the machines in which they are contained.

To the above and other ends which will hereinafter appear, my invention consists in the features of construction, combinations of devices, and arrangement of parts set forth in the following description and particularly pointed out in the claims.

In the accompanying drawings wherein like reference characters indicate corresponding parts in the different views,

Figure 1 is a front view of a platen shown equipped with card clamping devices of my invention.

Figure 2 is an enlarged transverse sectional view of the same taken on the line 2—2 of Figure 1 and looking in the direction of the arrows at said line.

Figure 3 is an enlarged transverse sectional view of the same taken on the line 3—3 of Figure 1 and looking in the direction of the arrows at said line.

Figure 4 is a fragmentary detail sectional view taken through the card clamp and fastening means therefor at the left-hand end of the platen, the section being taken on the line 4—4 of Fig. 2 and looking in the direction of the arrows at said line.

Figure 5 is a corresponding fragmentary sectional view taken through the fastening means at the right-hand end of the platen, the section being taken on the line 5—5 of

Fig. 3 and looking in the direction of the arrows at said line.

55

I have shown my invention in the present instance in connection with a platen of a Remington-Noiseless No. 6 machine, which also is similar to that employed in the No. 5 Noiseless machine. In both instances the platen is made throughout of metal, and is closed at its ends by permanently secured end plates or heads which are flush with the ends of the cylindrical body. These platens do not readily lend themselves to the attachment thereto of card clamps or attaching means therefor heretofore in use. For several reasons it is desirable not to provide a special platen, nor to change, modify or mutilate the existing platens in order to provide attaching means for detachably connecting a card clamp thereto. This is especially true in platens such as those above referred to, although it also is true of platens generally. Among other reasons it would be difficult, if not impossible, for a mechanic in the field to effect such modification of the platen as might be necessary to equip the platen with such attaching means.

75

By my present invention, I provide simple and highly efficient means by which an existing platen of either of the machines mentioned may be readily equipped with a card clamp and its means for readily and firmly attaching it to or detaching it from the platen, without making any changes in the existing structures of the platens. While I have shown the invention in connection with platens of the machines mentioned, it will be understood that the advantages stated above are alike applicable to other typewriting and like machines and that the devices of my invention are of general application.

95

The main cylindrical metal body 1 of the platen is permanently closed at its ends by platen heads 2 and 3 which are flush with the ends of the platen. The platen at its left-hand end carries an outwardly projecting hollow spindle 4 fixed to the platen, whereas a solid spindle 5 projects outwardly from and is fixed to the platen at its right-hand end. A card clamp carrier or support, designated as a whole by the reference numeral 6, is detachably secured to the

100

105

spindle 4 adjacent to the associated platen head 2. This detachable carrier, in the present instance, comprises two sheet metal semi-circular clamping members 7 and 8 pivotally united at their overlapping ends, as indicated at 9. The opposite end of each of these members is formed with an outwardly projecting ear 10, that extends at right angles to the plane of the member of which it forms part. The ears have registering holes therein through which a headed screw or bolt 11 passes freely. The threaded end of the screw receives a nut 12. By tightening the screw 11 the members may be drawn together firmly clamping the carrier on the spindle 4. This structure enables the carrier 6 to be readily attached to or detached from the platen without cutting, tapping or otherwise modifying or changing the platen structure. The outermost overlapping end portion of the member 7 of the carrier is held a short distance away from the associated platen head 2, due to the underlying or interposed member 8 being next to said platen head 2, as best shown in Fig. 4. A radial arm 13 is formed on the member 7 and terminates in a cross head 14 (see Fig. 2) that is within the projected outline of the surface of the platen 1, and is in the plane of the member 7, so as to be held slightly spaced apart from the associated platen head. The radial arm 13 and cross head 14 provide a substantially T-shaped part which constitutes a connecting device or one member of a two-part detachably connected hinge for the card clamp 15, the other member of which is on the card clamp, as will presently appear.

The card clamp, aside from its connecting means, is of the type disclosed in the patent to Steele, No. 990,919 dated May 2, 1911. Thus, it will be seen the card clamp, designated as a whole by the reference numeral 15, is of a length substantially coextensive with the platen, and is curved in cross-section to conform substantially to the curvature of the surface of the platen against which it is adapted to be held. Each longitudinal edge of the clamp is undercut at 16 and 17 to provide between the overlapping body portion of the card clamp and the platen a groove or pocket in which an edge of the card or work sheet may be inserted and held during the feed of the card with the platen. The bottom edge of the card is inserted in the groove 16 when a backward feed of the card is to be effected, whereas the leading edge of the card is inserted in the groove 17 when a forward feed of the card is to be effected. Cam fingers 18, which lie snugly against the surface of the platen when the clamp is in place, extend beyond the edge of the clamp which contains the undercut groove 17. This is in order to cam off the usual paper scale

etc. which might be engaged by this edge of the clamp during backward feed of a card, as fully explained in said hereinbefore mentioned Steele patent. This renders it desirable to provide attaching means for the card clamp which will preclude the possibility of the clamp being secured wrong edge up on the platen, and such means have been provided in the present instance, as will presently appear.

The left-hand end of the clamp 15 is provided with an ear 19 that extends at substantially right angles to the body portion of the clamp and terminates in two inwardly directed fingers 20 with an intervening space 21. This construction provides the second member of the two-part detachable hinge, hereinbefore referred to, and with which the other T-shaped member coacts. When these members are united, the arm 13 is received in the space 21, whereas the cross head 14 is received in the pockets formed by the fingers 20. This construction provides for detachably hinging one end of the clamp to the platen, so that the normally slightly bowed clamp 15 may, by a pivotal movement, be forced against the face of the platen to its card holding position, or may be moved in the opposite direction to a position at substantially right angles to the axis of the platen, when the card clamp may be detached from the platen.

The means for detachably securing the opposite end of the card clamp to the platen will now be described. A carrier, somewhat like that previously described, is detachably connected to the spindle 5 at the opposite end of the platen. Said carrier comprises two semi-circular members 22 and 23 pivoted together at 25, and firmly clamped on the spindle 5 by a screw bolt. One member 22 of this carrier is provided with two oppositely disposed catches, engaging members, or fastening devices 27, 28, each mounted on a headed pivot 29 carried by the part 22. An outwardly projecting perforated ear 30 is formed on each catch for connection therewith of one end of a contractile spring 31, by which the outer ends of the catches are drawn together to the locking position. The catches have oppositely disposed engaging bills or members 32 from which extend oppositely disposed outwardly directed bevel faces 33, for purposes which will hereinafter appear. The catch 27 has a tooth 34 which extends into an interdental opening 35 in the other catch. The inner wall 35^a of this opening is slightly beveled away to permit the tooth 34 to rock therein. Outwardly, beyond the tooth 34, each catch is provided with an abutting face or stop 36 which limits the movement of the outer ends of the catches towards each other when the abutting faces are in contact, in the event that the spindle

5 does not effect such limit of movement. The interlocking connecting means just described between the two catches, and which include the tooth 34, compel both catches 5 to move together into and out of effective position. It follows, therefore, that in releasing the catches from engagement with the card clamp, it is merely necessary to move either catch and the other will receive 10 a corresponding movement, thereby facilitating the disengagement of the catches from the clamp with one hand.

It will be seen that the member 22 of the right-hand carrier is formed with a radially 15 disposed outwardly projecting finger or guide 37 that is situated out of the plane of the catches 27 and 28 but midway between the two. This finger, when the clamp is in place, is adapted to be received in a space 20 38 between two outwardly extending lugs 39 on an ear 40 that projects from one end of the card clamp at substantially right angles to the plane thereof. This centers the lugs 39 between the two catches and interlocking connection prevents the clamp 15 from moving around the periphery of the platen, whereas the bills 32 of the catches are adapted to engage over the lugs 39, and 25 positively lock and firmly hold the clamp 30 against the face of the platen at this end thereof.

The catch carrying members 22 and 23, like the carrier 6 at the opposite end of the platen, is detachably connected to the platen, is detachably connected to the platen 35 by means similar to those previously described. Thus, each of the members 22 and 23 is provided with an outwardly extending perforated ear 41. A screw bolt 42 passes through the aligned openings in said ears 40 and has a nut 43 on the threaded end thereof. By tightening the screw bolt 42 the members 22 and 23 may be drawn together and firmly 45 clamped on the right-hand spindle 5, thus connecting the carrier for the catches to the platen. By removing the bolts 11 and 42 the carriers for detachably connecting the card clamp to the platen may be readily removed.

It will be seen that by the use of the detachable carriers described above, it is unnecessary to mutilate, modify, tap, or in any 50 manner change standard platens in order to apply the card clamp and its fastening means thereto or to remove such parts therefrom. When the card clamp is removed from the platen, it remains a standard platen for ordinary use.

When the card clamp is moved into effective position around its hinged end the outer side edges of the lugs 39 will coact with the bevel faces 33 of the catches while the inner edges of the lugs coacting with the finger 37 will direct the free end of the clamp to proper position. The action of the lugs 39 on the bevels 33 will force the 55 catches away from each other against the

power of the spring 31 until the lugs pass the bills 32 of the catches, when the latter under the action of the spring 31 will snap over the lugs into locking position and firmly and positively hold the clamp in position 70 on the platen.

The self-acting spring-closed catches or fastening devices materially aid in quickly attaching the clamp to the platen, and the shifting of either catch to releasing position 75 releases both catches. When thus released, the clamp may be turned on its hinge to a position at substantially right angles to the axis of the platen. In this position, the hinge member on the clamp may be detached 80 from the hinge member on the carrier 6 and the clamp may be removed.

It will be seen that I have provided simple and efficient means whereby a card clamp and its attaching means may be readily applied to a platen without reconstructing, modifying, tapping, drilling or altering the platen in any manner and that after the attaching means are once applied the clamp may be quickly attached or detached, and when attached is effectively held on the platen.

What I claim as new and desire to secure by Letters Patent is:—

1. In a typewriting or like machine, the combination of a platen, a card clamp substantially coextensive with the length of the platen, and means for detachably connecting said card clamp to the face of the platen, said means comprising a locking projection 95 on said clamp outwardly extending beyond one end of the platen when the clamp is in place, and two oppositely disposed spring-pressed catches carried by the platen and which are self-locking and positively engage 100 said locking projection when the clamp is moved to effective position on the platen and positively prevent the detachment of the card clamp from the platen until said 105 catches are hand released.

2. In a typewriting or like machine, the combination of a platen, a card clamp substantially coextensive with the length of the platen, means for detachably connecting said card clamp to the face of the platen, 115 said means comprising two detachably connective hinge members for hinging the clamp at one end of the platen, one of said members being formed from an integral ear on said clamp, a locking projection on the opposite end of the clamp, and a spring actuated self-locking catch that positively engages 120 said locking projection when the clamp is moved to effective position on the platen and positively prevents the detachment of the card clamp until said catch is hand released.

3. In a typewriting or like machine, the combination of a platen, a card clamp substantially coextensive with the length of the 125 130

- platens, means for detachably connecting said card clamp to the face of the platen, said means comprising a locking member on the card clamp, two self-locking catches which coact with said locking member and positively engage it on opposite sides when the clamp is moved to effective position on the platen and positively prevent the detachment of the card clamp from the platen until said catches are released, and intermediate controlling connections between said catches by which a movement of one catch to releasing position will cause a corresponding movement of the other catch.
4. In a typewriting or like machine, the combination of a platen, a card clamp substantially coextensive with the length of the platen, means for detachably connecting said card clamp to the face of the platen, said means comprising two supporting members having means by which they may be readily, fixedly, and firmly attached to or detached from the platen at opposite ends thereof without altering or mutilating the platen, engaging means carried by each of said supporting members, and connecting means at opposite ends of the card clamp which coact with said engaging means to positively though detachably connect the card clamp to said supporting members and positively hold the card clamp against the face of the platen.
5. In a typewriting or like machine, the combination of a platen, a card clamp substantially coextensive with the length of the platen, means for detachably connecting said card clamp to the face of the platen, said means comprising a supporting device made up of two relatively movable members having means for drawing them together for detachably connecting the supporting device to the platen at one end thereof without altering or mutilating the platen, engaging means carried by said supporting device, and engaging means carried by said card clamp at one end thereof and co-operative with the engaging means on said supporting device to aid in positively though detachably connecting said card clamp to the platen.
6. In a typewriting or like machine, the combination of a platen, a card clamp substantially coextensive with the length of the platen, means for detachably connecting said card clamp to the face of the platen, said means comprising a supporting device made up of two relatively movable members having means for drawing them together for detachably connecting the supporting device to the platen at one end thereof without altering or mutilating the platen, two spring actuated locking catches pivoted on said supporting device, engaging means on said card clamp that is positively engaged by said catches when the card clamp is posi-

tioned on the platen, and means for detachably connecting the other end of the card clamp to the platen.

7. In a typewriting or like machine, the combination of a platen having a spindle, a card clamp, and means for detachably connecting said card clamp to and positively holding it against the face of the platen, said means comprising a supporting device having means for rigidly and firmly though detachably clamping the supporting device directly to said spindle to turn therewith without altering or mutilating the platen, a fastening device carried by said supporting device, and companion interlocking means carried by the card clamp to aid in positively though detachably connecting the card clamp to said supporting device.

8. In a typewriting or like machine, the combination of a platen having a spindle projecting from both ends thereof, a card clamp, and means for detachably connecting said card clamp to the platen without altering or mutilating the platen, said means comprising two carriers having means for detachably clamping them on said spindles near the ends of the platen, a detachable hinge, one member of which is carried by one of said carriers and the other member of which is carried by the card clamp at one end thereof, and means for positively though detachably connecting the other end of the card clamp to the other carrier including a catch spring-actuated to locking position when the clamp is moved on its hinge to effective position against the platen and positively engaging a companion engaging member to hold the clamp in place.

9. In a typewriting or like machine, the combination of a platen having a spindle projecting from both ends of the platen, a card clamp, and means for detachably connecting said card clamp to the platen without altering or mutilating the platen, said means comprising two carriers detachably mounted on said spindle and each made of two parts pivoted together and connected by a screw by which the parts may be drawn together to clamp the carrier on its spindle, and means for detachably connecting each end of said card clamp to one of said carriers.

10. In a typewriting or like machine, the combination of a platen having a spindle projecting from both ends of the platen, a card clamp, and means for detachably connecting said card clamp to the platen without altering or mutilating the platen, said means comprising two carriers detachably mounted on said spindle and each made of two parts pivoted together and connected by a screw by which the parts may be drawn together to clamp the carrier on its spindle, one part of a detachable hinge being carried by one of said carriers, the other part of

said hinge being formed from the card clamp at one end thereof, a pair of spring-closed catches carried by the other of said carriers, and an engaging projection on the 5 card clamp at one end thereof with which said spring catches are adapted to engage.

11. In a typewriting or like machine, the combination of a platen having a spindle projecting from both ends of the platen, a 10 card clamp, and means for detachably connecting said card clamp to the platen without altering or mutilating the platen, said means comprising two carriers detachably mounted on said spindle and each made of 15 two parts pivoted together and connected by a screw by which the parts may be drawn together, to clamp the carrier on its spindle, one part of a detachable hinge carried by one of said carriers, the other part of said hinge 20 being formed from the card clamp at one end thereof, a pair of spring-closed catches carried by the other of said carriers, a bifurcated engaging projection on said card clamp with each arm of which one of said 25 catches is adapted to positively engage when the card clamp is turned on its hinge against the platen, and a projection on the companion carrier which is received between the arms of said bifurcated engaging projection 30 when the clamp is in place.

12. In a typewriting or like machine, the combination of a platen having a spindle projecting from one end thereof, a card clamp, and means for detachably connecting said card clamp to the platen comprising a carrier made of two parts pivoted together and connected by a screw by which the parts may be drawn together to detachably clamp and firmly hold said carrier on said spindle, 35 two oppositely disposed spring-closed catches pivoted on said carrier and having beveled faces, and an engaging member on said card clamp which when the clamp is moved into effective position on the platen coacts with 40

said beveled faces and causes the catches to 45 positively engage said engaging member and hold the clamp against the platen.

13. In a typewriting or like machine, the combination of a platen having a spindle projecting from one end thereof, a card 50 clamp, and means for detachably connecting the card clamp to the platen comprising a carrier detachably connected to the spindle at one end of the platen, a pair of spring-actuated catches pivoted on said carrier, intermediate controlling connections between 55 said catches by which a movement of one of the catches away from locking position causes a corresponding movement of the other catch, and an engaging member on said clamp 60 adapted to be positively engaged by said catches to hold the card clamp against the platen.

14. In a typewriting or like machine, the combination of a platen having a spindle 65 projecting from each end thereof, a card clamp, and means for detachably connecting the card clamp to the platen comprising a carrier detachably connected to the spindle at one end of the platen, a pair of spring 70 actuated catches pivoted on said carrier, intermediate controlling connections between said catches by which a movement of one of the catches away from locking position causes a corresponding movement of the 75 other catch, an engaging member on said clamp adapted to be positively engaged by said catches to hold the card clamp against the platen, a like carrier detachably connected to the spindle at the other end of the 80 platen, one member of a detachable hinge connection carried by said last mentioned carrier, and a second member of said hinge carried by said card clamp.

Signed at Middletown, in the county of 85 Middlesex and State of Connecticut this 26th day of August, A. D., 1925.

GEORGE G. GOING.
